GUN CLEARING DEVICE

Lautt F. Young, Corpus Christi, Tex.

Application March 8, 1948, Serial No. 13,729

8 Claims. (Cl. 89—1)

(Granted under the act of March 3, 1883, as
amended April 30, 1928; 370 O. G. 457)

The invention described herein may be manufactured and used by or for the Government for governmental purposes without payment to me of any royalty thereon.

This invention relates to a device mountable on gun chargers of well known types that is operable remotely to clear the gun of rounds and allow gun cooling to prevent accidental discharge of the gun after prolonged firing.

A potential hazard of machine guns, and particularly those fired automatically from a remote point, is the possible discharge of a round left in the gun after firing of considerable duration has ceased. The accidental discharge of the round left in the gun is caused by the heat from the gun barrel which is generated by extended firing. The time taken to discharge the round remaining in battery position is unpredictable since this time is dependent for the most part on the barrel temperature. The action of a round being accidentally exploded in the above manner is referred to generally by mechanics of the art as "cook-offs." It may be well understood that such "cook-offs" could cause serious material or personal damage and should be avoided.

The present invention is made to prevent "cook-offs" by utilizing a solenoid that is remotely controlled to actuate a lever means adapted to be pivoted into the path of the gun bolt stud to prevent the gun bolt stud from returning to battery position subsequent to its recoil position. The solenoid actuated device, or gun clearing device, is controlled remotely by a switch in a circuit which, when closed, breaks the circuit through the gun firing solenoid simultaneously with the operation of the gun clearing solenoid. By this means, the actuation of the gun clearing device prevents firing of the first round subsequent to the closing operation of the gun clearing switch which live round is ejected. Since the gun bolt stud can not return to battery position, another live shell can not be picked up by the belt feed pawl preventing reloading. In this manner, there is no live cartridge in the gun to "cook-off" and air may pass freely through the gun barrel to cool it.

It is a primary object of this invention to provide a gun clearing device for machine guns that prevents accidental discharge and permits gun barrel cooling.

It is another object of this invention to provide a means for preventing the gun bolt stud from entering the battery position wherein a live round is prevented from being positioned in bat-

tery and the gun barrel is left open for air cooling.

A further object of this invention is to provide a lever mechanism having a lever for being selectively positioned in the path of the gun bolt stud of a machine gun to prevent it from anti-recoiling to its battery position to effect gun unloading and gun barrel cooling.

It is still a further object of this invention to provide a solenoid actuated lever means positioned on the gun charger of a remotely controlled machine gun that is electrically controlled by a switched circuit with a relay means therein actuatable to break a gun firing solenoid circuit upon closing of the switch in the switched circuit, the lever adapted to be interposed in the path of the gun bolt stud to prevent it from anti-recoiling into its battery position wherein subsequent gun charging ejects any live shell in the gun T-slot eliminating accidental gun discharge and permitting passage of air through the gun barrel for cooling.

These and other objects will become more apparent as the description proceeds when taken in conjunction with the accompanying drawings, in which:

Fig. 1 is a partial view of a machine gun with the gun charger thereon incorporating the gun clearing device of this invention;

Fig. 2 is an elevational view of the gun clearing mechanism with parts shown in section and shown attached to a fragment of the gun charging cylinder;

Fig. 3 is an end elevational view of the gun clearing mechanism; and

Fig. 4 is a block wiring diagram of the gun charging device incorporating the gun clearing means.

Referring more particularly to Fig. 1, there is shown a machine gun 10 having a gun barrel 11 and an oil buffer 12 of the well known type. A gun charger of the type shown and described in the patent granted to Walter R. Weeks on February 5, 1946, bearing the Patent Number 2,394,127, generally referred to by the reference character 15, is mounted on the side of the gun 10 by the bolt 16 such that the gun bolt stud 17 passes through the slot 18 of a charging cylinder 19 of the gun charger in a manner well recognized in the art. The charging cylinder 19 is held in frame members 20, 21 and 22, the latter frame member 22 also housing a supply and exhaust valve 23 that extends therethrough and is actuated by a gun charging solenoid 24. Frame member 22 has an internal passage connecting

one side of the valve with the charging cylinder 19 for conducting fluid under pressure to one side of a piston therein (not shown) to thrust the gun bolt stud to the left end of the slot 18, or its recoil position, it being returned to the position shown in this figure, or the battery position, by spring means within the gun to initially charge the gun in the well known manner for firing. The conduit 25 is adapted to be connected to a source of air under pressure or a gas cylinder, as carbon dioxide, to supply the charging pressure to the charging cylinder as is also well known in the art.

The gun firing solenoid 28 is positioned near the gun charging solenoid 24 on the sub-frame members 29 and 30 and actuates a sear slide 31 through a bell-crank linkage 32 to cooperate with the firing pin detent to condition the gun for firing or nonfiring as is well known in the machine gun art.

A timer 35 is also within the frame of the gun charger 15. This timer is not shown in full detail since it forms no part of the present invention and its construction and operation is fully illustrated and described in the above-mentioned patent to Walter R. Weeks. Principally, the timer consists of a motor 36 geared to a shaft 37 on which two bell-crank levers 38 are frictionally clutched. Each bell-crank lever has a portion 39 engageable with an extension 40 of a switch operative to control circuits later to be described. A lever 41 pivoted on the shaft 37 extends into the slot 18 of the charging cylinder 19 in the path of the gun bolt stud 17. Upon recoil of the gun, the gun bolt stud 17 will strike the lever 41 pivoting it rearwardly. The lever 41 carries the cross bar 42 that engages the bell-crank levers 38 turning them clockwise against the friction of their respective clutches to prevent the bell-crank lever portions 39 of each from engaging the associated switch actuator lever 40. A lever 43 has one portion that engages the cross bar 42 and a cam portion that is adapted to be engaged by the piston of the charging cylinder to effect lifting of the bar 42 to permit the bell-crank lever 39 to advance to the associated switch actuator lever 40 to control the gun circuit in a manner later to be more fully described.

Referring to Figs. 2 and 3 in addition to Fig. 1, there is shown attached to the frame member 21, as by bolts 50, a block 51 on which are pivoted two arms 52 and 53 by a shaft 54 fastened thereon by pins 55. The block 51 has a centrally located notch 56 (see Fig. 3) through which the shaft 54 extends. An actuator cam lever 57 operates within the notch 56 and is fixed to the shaft 54 by a pin in the same manner as the arms 52 and 53, the actuator cam lever 57 being positioned slightly less than 180 degrees from the arms 52, 53, as shown in Fig. 2. On the lower edge of the arms 52 and 53 and the block 51 are studs 58 for supporting tensioning springs 59 which bias the arms 52 and 53 in the counterclockwise direction, as best understood from viewing Fig. 1, in which the arms are out of the path of the gun bolt stud 17.

A gun clearing solenoid actuator 60 is held to the gun charger through frame members 61 and 62 that are mounted on the frame member 21 as by bolts or screws 63. The solenoid 60 has an extension 64 through which is axially journaled an actuator pin 65 mechanically connected to the solenoid armature. The solenoid extension 64 has a flattened portion 66 at its outer end on

which is pivotally supported a bifurcated flipper lever 67 at a point substantially below the longitudinal center line of the actuator pin 65. The end of the flipper lever 67 opposite the pivot has a cam portion 68 that cooperates with the cam portion of the actuator cam lever 57. Upon energization of the gun clearing solenoid 60, the pin 65 is thrust outwardly to rotate the flipper lever 67 counterclockwise which rotates the actuator cam lever 57 clockwise to position the arms 52 and 53 in the path of the gun bolt stud 17. This action takes place to shift the gun clearing means from an inactive to an active position as shown in Figs. 1 and 2, respectively, in which Fig. 1 shows the position of the gun clearing parts when the gun clearing solenoid 60 is de-energized and Fig. 2 shows the gun clearing position when the solenoid 60 is energized. The gun clearing solenoid 60 is electrically connected through the conductor 69.

In order to better understand the circuit means for operating a machine gun including the gun clearing device, it is best to refer to Fig. 4 in which like parts shown in block form representing the elements of the former figures have like reference characters and the elements shown diagrammatically and corresponding to elements of the former figures have primed reference characters of those in Figs. 1, 2 and 3. In Fig. 4, the positive side of a potential source, as a battery 75, is connected to one side each of two normally open switches 76 and 77, shown with legends and referred to hereinafter as gun clearing and gun firing switches, respectively. The supply side of the gun firing switch 77 is connected through a conductor 78 to the contact 79 of a normally closed switch A in timer 35 and the contact 80 of this switch A is connected to the timer motor 36 (Fig. 1) and to contact 81 of a normally open switch B of timer 35. Contact 82 of switch B is connected to the gun charging solenoid 24 through the conductor 83. The supply side of the gun firing switch 77 is also connected through a conductor 85 and a normally closed relay switch 86 to the gun firing solenoid 28.

The supply side of the gun clearing switch 76 connects the electromagnet of the relay switch 86 and the gun clearing solenoid 60 in parallel through conductors 87 and 69 such that when switch 76 is closed the relay will break the circuit to the gun firing solenoid 28 and energize the gun clearing solenoid 60.

In operation, and considering that the above described machine gun device is in an aircraft for the purpose of illustration, when the pilot desires to fire the gun, he depresses the gun firing button to close switch 77. A circuit is now closed through the switch A and timer motor 36 and at the same time the circuit is closed through the relay switch 86 and the gun firing solenoid 28 wherein the gun firing solenoid operates through the bell-crank linkage 32 to position the sear slide 31 to allow gun firing upon operation of the gun mechanism. The timer motor 36 rotates to advance the bell-crank levers 39 and 39' toward their switch actuating positions in which lever 39' would close switch B and lever 39 would open switch A. The timer mechanism is constructed and arranged, as is well known in the art, to advance the switch B actuator 39' at a more rapid rate than the switch A actuator 39 such that in a fraction of a second of timing motor operation the switch actuator 39' for switch B will have advanced to

close switch B and close the circuit through the gun charging solenoid 24. The solenoid 24 actuates the valve 23 to supply gas under pressure to the cylinder 19 causing a piston 90 (shown in phantom) therein to force the gun bolt stud 17 to its recoil position where it strikes the lever 41' and the piston, at the same time, strikes the cam lever 43' to retract the switch B actuator 39' and to shift the cross bar 42' out of the path of the switch A actuator 39 such that the switch B opens but the actuator of switch A continues to travel toward its switch actuating opening position. The circuit to the gun charging solenoid being broken allows the valve 23 to return to cut off position and exhaust the charging cylinder 19 wherein the gun bolt stud 17 returns to battery position, as shown in Fig. 1. The action of the gun bolt stud through the above cycle effects through the mechanism of the gun automatic loading, firing and shell ejecting in the gun. Recoil, upon firing of the gun, kicks the gun bolt stud to recoil position in rapid successive cycles. Each time the gun fires only the gun bolt stud strikes the lever 41 which pushes both switch actuator levers 39 and 39' away from the switch arms 40 and 40' so that neither switch A or B is actuated during gun firing.

In the event that the gun does not fire, upon the gunner operating the switch (77) as before, the piston 90 in the gun charger will be actuated several times but, since the piston 90 strikes the cam lever 43' to withdraw the cross bar 42' out of the path of the actuator lever 39, this actuator lever 39 will proceed until it opens the switch A thus locking-out the gun. In order to recondition the gun for active operation it is necessary to manually depress a reset button 95 which is conveniently placed on the gun charger.

The above operation of the gun and gun charger is well known and is only repeated here to provide an unmistakable setting for applicant's device. In actual practice and after extended firing of a machine gun of the type described above, a live shell left in battery position upon cessation of firing has, in many cases, been fired or "cooked-off" due to the hot gun barrel. Obviously such a condition is not only dangerous but very undesirable. For instance, such "cook-off" may happen when a friendly plane passes before the gun or while aircraft personnel are working about it. Applicant's device prevents this in that at any time, whether or not the gun firing button is depressed, the gun clearing button may be depressed to close switch 76 which energizes the gun clearing solenoid 60 and operates the relay 86 to break the circuit to the gun firing solenoid to withdraw the sear slide 31 rendering the gun firing pin inactive. The energization of the gun clearing solenoid 60 effects a clockwise rotation of the arms 52, 53 from the position shown in Fig. 1 to that shown in Fig. 2. In the event this action takes place during the instant that the gun bolt stud 17 is in battery position, the gun bolt stud will force the arms 52 and 53 counterclockwise sufficiently to allow the gun bolt stud 17 to pass these arms to its recoil position since either the gun recoil action or the gun charging piston is stronger than the solenoid 60 through its operating linkage to the arms 52, 53. Thereafter the gun bolt stud 17 will strike the back side of the arms 52, 53, as shown in Fig. 2, which prevents further firing or subsequent reloading. The first cycle of gun bolt stud operation after the switch 76 has been closed, permits a live round to be carried in the T-slot of the gun but the live

round never reaches battery position. The second cycle of operation ejects the live round but another live round is not picked up wherein the gun remains empty. It is only necessary for the gun operator to hold the gun firing button 77 down a short time after depressing the gun clearing button 76 to permit the gun to go through at least two cycles. The gun being thus conditioned removes any possibility of "cook-offs" and at the same time allows cooling air to pass through the open gun barrel.

For subsequent firing of the gun, it is only necessary to depress the gun firing button 77 and the gun charging action will take place as explained, supra. When the gun bolt stud 17 travels to its recoil position the arms 52, 53 will be rotated counterclockwise by the springs 59 out of the path of the gun bolt stud 17.

From the foregoing, it may be readily understood that various modifications and changes in structure and arrangement of parts may be made without changing the spirit and scope of this invention and I desire to be limited only in the scope of the appended claims.

25 I claim:

1. In combination with a gun and a gun charger having a charging cylinder with a gun bolt stud slot therein for receiving the gun bolt stud, the improvement which comprises an element selectively movable across the gun bolt stud slot for selectively blocking the gun bolt stud from its battery position, resilient means biasing said element away from the gun bolt stud slot, and means for holding said element across the gun bolt stud slot against the bias of said resilient means.

2. In combination with a machine gun having an operating gun bolt stud and a gun charger having a gun firing solenoid and a charging cylinder with a gun bolt stud slot receiving the gun bolt stud, the improvement which comprises an element selectively movable across said gun bolt stud slot for blocking the gun bolt stud out of battery position, electro-mechanical motor means operatively associated with said element for actuating said element into gun bolt stud blocking position, means biasing said element to a position clearing said gun bolt stud and electrical circuit control means including said electro-mechanical motor for controlling said electro-mechanical motor means.

3. The improvement as set forth in claim 2 wherein said electrical circuit means includes means for rendering said gun firing solenoid inactive upon energization of said electro-mechanical motor means.

4. The improvement as set forth in claim 3 wherein said element comprises a pair of lever members fixed in the same angular relation to a shaft journaled on said charging cylinder, and said electro-mechanical motor means is an electromagnetic.

5. A gun clearing device in combination with a gun charger having a charging cylinder with a gun bolt stud slot comprising, a pivoted lever means adapted to be positioned across the gun bolt stud slot or away from said slot, resilient means biasing said lever means away from said slot, power means operatively associated with said lever means for positioning said lever means across said slot, and means for controlling said power means whereby operation of said power means to position said lever means across said slot prevents an associated gun from placing a cartridge in battery position.

6. A gun clearing device as set forth in claim 5 wherein said power means is an electromagnet and said means controlling said electromagnet is an electric circuit, said circuit including a relay for opening a gun firing circuit upon closure of said first mentioned circuit whereby an associated gun would be inactivated and cleared of live rounds.

7. A gun clearing device in combination with a gun charger having a charging cylinder with a gun bolt stud slot therein comprising, a pair of lever members pivotally supported on said charger cylinder adjacent one end of said slot, said levers being fixed in the same angular relation and spaced apart to straddle said charging cylinder and shorten said gun bolt stud slot in one pivoted position thereof, electromagnet power means operative to pivot said levers to said one pivoted position upon energization thereof and means resiliently biasing said levers to a second pivoted position away from said gun bolt stud slot, and circuit control means including said electromagnet power means whereby said levers can be selectively positioned.

8. A gun clearing device in combination with a gun charger having a charging cylinder with diametrically opposed gun bolt stud slots therein comprising, a pair of lever members axially spaced on a shaft in the same angular relation,

said shaft being journaled on said charging cylinder adjacent the battery end of said gun bolt stud slots on an axis parallel to a diameter of said charging cylinder such that the levers are rotatable to a gun clearing position in which they cover a portion of the battery end of said gun bolt stud slots on opposite sides of said charging cylinder and are rotatable to an inactive position in which the gun bolt stud slots are free of obstruction, spring means biasing said lever members to said inactive position, electromagnet means operatively associated with said lever members to rotate them to their gun clearing position upon electromagnet energization, and a circuit including controlling means for selectively energizing said electromagnet whereby said lever members are selectively placed in gun clearing position.
